UNITED STATES PATENT OFFICE.

CHARLES A. BABCOCK, OF BUFFALO, NEW YORK, ASSIGNOR TO PRATT & LETCHWORTH, OF SAME PLACE.

DESIGN FOR A CARRIAGE-STEP.

SPECIFICATION forming part of Design No. 15,758, dated February 3, 1885.

Application filed December 31, 1884. Term of patent 7 years.

To all whom it may concern:

Be it known that I, CHARLES A. BABCOCK, a citizen of the United States, residing at Buffalo, in the county of Erie and State of New York, have invented and produced a new and original Design for Carriage-Steps, of which the following is a specification.

This design relates to the ornamentation of the upper surface of a carriage step by means of ornamental ribs; and it consists of the special features which will be hereinafter described and claimed, and which are represented in the accompanying drawing, which represents a top plan view of the carriage-step.

A represents the plate of the step, square or rectangular in form and provided with round corners.

B B' B² represent three concentric rings on the plate A, and C represents a cross-shaped ornament in the inner ring, B.

D represents lily-shaped ornaments extending from the inner ring, B, to the corners of the plate A, and provided with internal ribs, d.

E represents leaf-shaped ornaments between the ornaments D and the inner ring, B, and the sides of the plate A.

f are openings in the plate A.

I claim—

The design for a carriage-step, consisting of three concentric rings B B' B², corner ornaments, D, and intermediate ornaments, E, substantially as shown and described.

Witness my hand this 19th day of November, 1884.

CHAS. A. BABCOCK.
